UNITED STATES PATENT OFFICE.

WILSON E. SYMONS, OF CHICAGO, ILLINOIS.

CAR-ROOF.

1,206,268.

Specification of Letters Patent. Patented Nov. 28, 1916.

Application filed November 30, 1912. Serial No. 734,376.

To all whom it may concern:

Be it known that I, WILSON E. SYMONS, a citizen of the United States, residing at Chicago, in the county of Cook and State of 5 Illinois, have invented a new and useful Car-Roof, of which the following is a specification.

The invention relates to improvements in car roofs.

- 10 In the ordinary type of car roof most generally used wherein the roof sheets extend from the center of the car to the outer edge or eaves, being nailed at the latter point, all torsional strains causing the dis- 60
15 tortion of the roof sheets result in either tearing the sheets at the eaves or facia or pulling them apart where they are joined by interlocking flanges or similar joints at the center or ridge pole, the failure usually be- 65
20 ing greater at the eaves or facia board for the reason that the fastening in the center or at the ridge pole is much more rigid, offering greater resistance than the fastening at the eaves. The rigidity of this center con- 70
25 nection is also reinforced by the location of the running board saddles, which are usually bolted down through the ridge pole with nuts on the inside of the car, thereby making the two roof sheets almost as solid as 75
30 though the two sheets were one continuous piece extending entirely across the car from one facia board to the other. To overcome these objectionable features my design of roof presents large center or floating sheets, 80
35 flexibly connected with narrow side sheets preferably at a point nearer the eaves than midway between the ridge pole and the eaves. By this design the torsional strains that tend to disrupt or injure the present 85
40 long roof sheets extending entirely across one half of the car are taken care of, and the large center or floating sheets and the narrow side sheets of the present roof are afforded free and easy movement at a point 90
45 near the eaves, thereby eliminating the possibility of damage either to the narrow sheets on the side or the large center floating sheets, which extend under the running board. The present roof also provides for 95
50 both lateral and transverse movement of the

roof sheets without distortion or injury to the same, the joints affording ample play both transverse and longitudinal for all possible movements of the roof structure, whether the car structure be of wood or 55 metal, that it might be called upon to meet in the most extreme service conditions whether on straight lines, hilly roads of sharp curvature or from rough switching in yards and terminals. 60

Another object of the invention is to provide a single layer self-sustaining roof structure adapted to eliminate the underneath boards or flooring or analogous wooden supports and to afford a clear view of 65 the roof for either interior or exterior inspection, to detect leaks, etc., and to provide a complete metallic roof of simple and comparatively inexpensive construction, which will be thoroughly water and weather proof 70 and in which there will be sufficient flexibility to prevent the sheets from being torn or pulled apart at the eaves line or facia. 75

A further object of the invention is to provide a metallic roof of this character 80 adapted to be readily applied to cars without necessitating any alteration in the construction of the car bodies or frames, or any special preparation of the same, and in which the central or major portion of the 85 roof will be composed of floating sheets and not be bolted, clamped, bound, or in any manner held so as to interfere with such freedom of movement as may be essential to avoid damage, and at the same time remain 90 weather and water proof. This differentiates the roof of the present invention as belonging to an entirely different class from those in common use wherein the roof sheets are joined to the center using some form of 95 inverted hood or covering to prevent the admission of water at the center joint.

Another object of the invention is to equip the roof with a running board, adapted to be applied to the roof in a completed 95 condition and capable of covering and protecting a large area of the same and of affording maximum safety to trainmen and of permitting them to pass one another without having to step upon the roof sheets. 100

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to 10 without departing from the spirit or sacrificing any of the advantages of the invention.

In the drawings:—Fig. 1 is a plan view of one end of a car roof, constructed in 15 accordance with this invention, portions of the running board and an intermediate center sheet being broken away to illustrate the construction more clearly. Fig. 2 is a side elevation of the same partly in section. 20 Fig. 3 is a central longitudinal sectional view. Fig. 4 is a transverse sectional view, taken substantially on the line 4—4 of Fig. 1. Fig. 5 is an enlarged transverse sectional view, taken centrally through one of 25 the transverse joints. Fig. 6 is an enlarged detail sectional view on the line 6—6 of Fig. 5. Fig. 7 is a detail perspective view, illustrating the construction of the end and intermediate roof sheets and showing one 30 of the central sheet caps. Fig. 8 is a detail longitudinal sectional view, taken through the center of the roof sheets. Fig. 9 is a similar view through the side roof sheets. Fig. 10 is a detail view of one of 35 the side sheet caps. Fig. 11 is a detail perspective view of one of the ridge pole blocks. Fig. 12 is a similar view of one of the center sheet cap filler blocks. Fig. 13 is an enlarged detail sectional view on the line 40 13—13 of Fig. 1. Fig. 14 is a detail sectional view on the line 14—14 of Fig. 5. Fig. 15 is a detail perspective view of one of the running board holders. Fig. 16 is a horizontal sectional view, taken substantially 45 on the line 16—16 of Fig. 6.

Like numerals of reference designate corresponding parts in all the figures of the drawings.

In the accompanying drawings in which 50 is illustrated the preferred embodiment of the invention, the metallic roof comprises in its construction relatively large end and intermediate center sheets 1 and 2, and relatively small end and intermediate outside 55 or side sheets 3 and 4, arranged in transverse sets or series and having transverse joints connecting the sets of the center and side sheets and supported by carlines 5, the number and location of which correspond with 60 the size of the roof sheets, a carline being located beneath each of the said transverse joints in flush relation with the upper edges of the side plates 6^a of the car body. The side sheets are supported upon the upper 65 edges of the side plates 6^a, and the carlines

5 are preferably constructed of metal and are approximately U-shaped, being provided at their side edges with spaced longitudinal flanges, as clearly illustrated in Fig. 3 of the drawings. The side flanges are preferably sheared off at the ends and the top portion bent downwardly to form attaching legs 6, which are bolted or otherwise secured at the inner faces of the side plates of the car. In addition to the carlines, the 75 roof is supported by central and side purlins 7 and 8, preferably constructed of wood, and the central purlin constitutes a ridge pole. The center sheets are supported upon the purlins 7 and 8 above the plane of the 80 side sheets, which are arranged upon the carlines.

The central and side ends sheets 1 and 3 are provided at their outer transverse edges with downwardly bent flanges 9 and 10, 85 which are secured by nails, bolts or screws to the end plate of the car. The end and intermediate outside or side sheets are provided at their outer longitudinal edges with downwardly bent flanges 11 and 12, which 90 are secured by screws, bolts or nails in the side plates of the car. The end and intermediate side sheets are also provided at their inner longitudinal edges with approximately L-shaped flanges 13 and 14, extending 95 upwardly and inwardly and supported upon the side purlins against the outer portions of which the L-shaped flanges fit. The side portions of the center sheets overlap 100 the inner longitudinal portions of the side sheets and are provided at their side edges with downturned side flanges 15 and 16, located at the outer side edges of the side purlins and fitting against and engaging 105 the upwardly extending L-shaped flanges of the side sheets 3 and 4.

The end and intermediate center sheets are provided at their adjacent transverse edges with upturned flanges 17 and 18, separated a distance equal to the size of a ridge 110 pole block 19 and center sheet cap filler blocks 20 and overlapped and engaged by center sheet caps 21, which span the spaces between the center sheets. Each center sheet cap 21 is approximately U-shaped in cross section, 115 being composed of a top portion and depending side flanges 22, between which are arranged the upturned flanges 17 and 18 of the center sheets. The center sheet caps are of a length to extend across the center sheets, and they terminate at the inner edges of the side sheets and at the ends of the upturned flanges 17 and 18. Also the space 120 between the depending side flanges 22 of the center sheet caps is greater than the space between the upturned flanges 17 and 18 to permit movement or flexibility without bending the said flanges.

The ridge pole block 19 is arranged with 125 in the center sheet cap at the center thereof

and supports the same, and it is secured upon the central purlin or ridge pole by a vertical bolt 23, passing through a central opening in the block 19 and having a polygonal head 24, which is seated in a recess 25 in the upper face of the block 19, as as clearly illustrated in Fig. 5 of the drawings. The bolt passes through the center purlin or ridge pole and through the supporting carline, and it is provided at its lower threaded end with a nut engaging the lower face of the top portion of the carline. The center sheet cap filler blocks, which are mounted upon the side purlins, have central bolt openings and are provided at their upper faces with annular bosses 26, surrounding the upper end of the bolt opening and fitting within flanged openings 27 of the center sheet cap. The center sheet cap is supported at its ends by the filler blocks, which are secured in place by bolts or studs 28, piercing the side purlins and the top portion of the carline and having threaded upper and lower ends 29 and 30. The upper threaded ends 29 engage threaded sockets 31 of running board holders 32, and the lower threaded ends 30 of the studs 28 receive nuts 33, which engage the lower face of the top portion of the carline 5.

30 The outside or side sheets 3 and 4 are provided at their adjacent ends with transverse joints consisting of an upturned flange 34 and an approximately V-shaped flange or portion 35 arched over and forming a cap for the upturned flange 34. The upturned flange 34, which is vertical, is located centrally or midway of the transverse planes of the upturned flanges 17 and 18 of the center sheets 1 and 2, and the corner of 40 the sheet having the flange 34 is cut away at the inner end thereof to provide a recess 36 to enable the side plate to fit the adjacent corner of the center sheet cap filler block 20. The arched overlapping approximately V-shaped portion 35 is composed of oppositely inclined sides or wings, one of which extends upwardly, from the end of the sheet having the arched portion 35, to a point above and in spaced relation to the 45 upper edge of the upturned flange 34, and the other inclined side or wing extends downwardly over the sheet having the upturned flange 34 to a point in spaced relation with the same, as clearly illustrated in 50 Fig. 6 of the drawings. The flanges 34 and 35 are of a length to extend across the side sheets from the inner upwardly extending L-shaped longitudinal flanges 13 and 14 to the outer downturned flanges 11 and 12.

55 The transverse edges of the center sheets are supported upon the purlins 7 and 8, and the transverse edges of the outer or side sheets rest upon the end portions of the carlines. The outer ends of the transverse joints of the side sheets are covered by side

sheet caps 37, preferably consisting of castings and composed of an outer vertical portion 38 and a substantially V-shaped top portion 39, extending from the inner face of the vertical portion 38 and composed of oppositely inclined sides or wings, which fit the V-shaped flange or portion 35. The vertical portion 38, which is secured to the side plate of the car by bolts, screws, or other suitable fastening devices, is recessed at its inner face at 40 providing spaces for the end portions of the downturned flanges of the side sheets and leaving an unrecessed portion 41, which fits against the side plate of the car between the downturned flanges 11 and 12 of the side sheets.

Each terminal of the center side cap and the inner end of the adjacent transverse flange of the side sheets are covered and protected by metallic casings 42 of the running board holder 32, which preferably consists of a casting. The running board holder 32 comprises a central vertical stem 43, an upper pocket 44 or 45, and the said lower casing 42, which is composed of the top spaced depending sides and the connecting end flange or wall, which is provided at the bottom with a central V-shaped recess 46 to receive the transverse joint of the side sheets, as clearly shown in Fig. 6 of the drawings. The top wall or portion of the casing 42 is provided with an interior recess 47 into which extends the boss 26 of the filler block 20 and the flanged opening 27 of the center sheet cap 21. The threaded socket 31 is formed in the lower portion of the stem 43 and extends upwardly from the recess 47, as clearly shown in Fig. 5, and the bolt or stud 28 securely fastens the running board holder to the adjacent side purlin and carline.

The pocket 44, which is located at one side of a running board 48, consists of a horizontal bottom, vertical side walls and an outer vertical connecting end wall, the pocket 44 being open at the top and inner end, as clearly shown in Fig. 15. The other pocket 45, which is located at the opposite side of the running board 48, is composed of a bottom, vertical side walls, a vertical outer end wall and a top wall 49, the pocket 45 being open only at the inner end, but the running board may be equipped at each side with either an open or closed pocket. The construction shown, however, is preferable as supporting cross pieces 50 or saddles of the running board may be readily introduced into the pockets 45 and then dropped into the pockets 44 and secured to the same by a single bolt 51. The running board consists of a series of planks or pieces supported at intervals by the cross pieces or saddles 50 to which they are suitably secured. The saddles or cross pieces 50 project at the sides of the running board to fit 130

the pockets 44 and 45. The running board is of sufficient width to permit trainmen to pass one another without stepping upon the roof sheets, and as it extends practically entirely across the center sheets, it protects the same besides affording maximum safety to the trainmen. The roof will be fully protected from the action of the trainmen and others who pass over cars frequently running or jumping on them in a manner which would materially damage the roof sheets unless there be a layer of boards underneath the roof, which supporting layer of boards is eliminated by the use of the wide running board of the present invention.

The running board projects beyond the end of the car and is supported by inclined end braces 52, secured to the end braces 52^a of the car and to end transverse supports 20 or saddles 53. The car is also equipped at each end with a lateral extension 54 of the running board, extending from the side of the car to the adjacent side of the running board and consisting of boards or pieces 25 secured to the upper edges of spaced transverse bars 55, having their inner end portions 56 extending beneath the running board and supporting tapered blocks 57, secured to the bars 55 and to the adjacent 30 planks or pieces of the running board by vertical bolts, or other suitable fastening devices.

In assembling the parts, the roof sheets are placed in position commencing from 35 either end of the car. The major portion of the roof is composed of relatively large unattached center sheets, which are practically what might be called "floating sheets," as they are imperforate and not bolted down 40 at any point and, therefore, there is absolutely no possibility of these sheets being torn or pulled out of shape by the torsional strain transmitted to the car roof. Neither 45 can the side sheets be pulled loose from the eaves or elsewhere for the reason that they are not fastened at the center of the car, the point of connection being much nearer the eaves than midway between the eaves and the center of the car roof, and, therefore, the 50 relatively narrow sheets at the sides of the car will receive no injury from the movement of the car body. Neither can the relatively small side sheets transmit any pulling 55 strains to the center sheets for the reason that they are not bolted together, and on account of this freedom from the pulling and tearing effect, which injures or destroys the outside roofs in present use, they will practically last the life of the car without becoming defective by the action of the car in 60 service.

In the present design of flexible car roof using the center type of floating sheets, it is 65 preferable to construct the sheets of a size to cover approximately sixty to seventy per

cent. of the entire area of the car roof, and it is feasible to use sheets of greater width or length than is at present used in common practice. In fact sheets six feet in length can be used with good results, while the present sheets are only about twenty-four to thirty inches, thus requiring by the present practice sixteen sheets on each side of a car approximately forty feet long, or a total of thirty-two sheets, while in my type of roof in which I eliminate the center connection at the ridge pole, using in its stead two joints or connections at a point nearer the eaves than the center of the car, the sheets when constructed six feet in length will only require a total of seven sheets to cover the car there being three rows, thus making twenty-one sheets in all.

The invention is not to be understood to be limited to any particular location of the longitudinal connection between the center and side sheets. In some car designs this might be brought up, say close to twelve or fourteen inches from the eaves or facia, while in others it might be located midway between the eaves or center of the car or ridge pole. Again the contour lines of the car roof viewed cross sectionally are not confined to any particular circle or radius. In fact the center or floating sheets may be made almost flat or level with just sufficient curvature to permit water to run off the roof, while the side sheets might be of a much smaller radius. This will be governed by the type and general design of the car to which the roof is to be applied. Some of the extremely large cars used for automobiles, buggies, etc., are now built as high as possible for passing through tunnels, and it is desired to get all of the clearance that can be secured at the eaves or facia so as to provide as much cubic space inside the car as possible, and in such cases the narrow side sections or sheets of the roof will probably be arranged at a much sharper angle or radius than the central portion or section of the roof. In bending the sheet metal to make the flanges, the sheet metal may be rounded at the corners instead of square, as shown in the accompanying drawings, the square bends being made in the said drawings for convenience of illustration.

What is claimed is:—

1. A single layer self sustaining flexible metallic car roof including relatively large unattached floating center sheets extending across the ridge or center line of the car roof and terminating at points intermediate of the center line and the eaves, and relatively small side sheets secured at their outer edges and constituting marginal portions of the car roof, the adjacent edges of the center and side sheets being arranged in loose overlapping relation so as to permit free relative movement of such overlapped parts and con-

sequent free movement of the unattached floating sheets.

2. A flexible metallic car roof including imperforate unattached floating center sheets extending across the ridge or center line of the car roof and terminating at their side edges at points approximately midway between the ridge or center line and the eaves of the roof, said floating center sheets constituting the major portion of the area of the car roof, and side sheets secured at the eaves and constituting the marginal portions of the car roof, said side sheets and center sheets having their adjacent edges arranged in loose overlapping relation to permit free movement of the unattached floating sheets.

3. The combination with a car body, of carlines extending across the car body, and side purlins located at opposite sides of and spaced from the center of the car body and supported by the carlines, and a roof including center floating sheets extending across the center of the car to points intermediate of the center and the side edges of the roof and supported at the side edges upon the side purlins, and side sheets secured at their outer edges to the car body, the inner longitudinal edges of the center and side sheets being arranged in loose overlapped relation at the said purlins.

4. The combination with a car body, of carlines extending across the car body, and side purlins located at opposite sides of and spaced from the center of the car body and supported by the carlines, and a roof including side sheets supported upon the carlines and having their outer edges secured to the car body and provided at their inner longitudinal edges with upwardly extending flanges supported upon the side purlins, and center floating sheets extending across the center of the car to points intermediate of the center and the side edges of the roof and supported upon the side purlins and provided at their side edges with downturned flanges engaging with the upwardly extending flanges of the side sheets to form a loose overlapped connection, the members of which have free relative movement.

5. The combination with a car body, of carlines extending across the car body, and side purlins located at opposite sides of and spaced from the center of the car body and supported by the carlines, and a roof including side sheets supported upon the carlines and secured at their outer edges to the car body and provided at their inner edges with upwardly extending approximately L-shaped flanges fitted against the outer portions of the purlins and supported by the same, and center sheets extending across the center of the car to points intermediate of the center and the side edges of the roof and supported upon the side purlins and extend-

ing over the L-shaped flanges of the side sheets and provided at their side edges with downturned flanges located at the outside of the said L-shaped flanges.

6. A single layer self-sustaining flexible metallic car roof including unattached floating center sheets having spaced side edges, marginal side sheets fixed at their outer edges at the eaves and extending inwardly therefrom to the center sheets and having a loose connection therewith, a center roof sheet cap extending over and loosely receiving the transverse edges of the center sheets and terminating at the inner longitudinal edges of the side sheets, and fastening means located inwardly of the loose connection between the side and the center sheets at the spaces between the said transverse edges of the same for securing the cap over the center sheets without interfering with the free movement thereof.

7. A single layer self-sustaining metallic car roof including center floating sheets extending across the center of the car to points intermediate of the center and the side edges of the roof and arranged in spaced relation and provided at their adjacent transverse edges with upwardly extending flanges, a transversely disposed center sheet cap extending across the center sheets and fitted over the upturned flanges thereof and provided with spaced side flanges between which the upturned flanges extend, and means located beyond the edges of the center sheets for supporting a running board.

8. A metallic car roof including relatively large center floating sheets, relatively small side sheets secured at their outer edges, the adjacent edges of the side and center sheets being loosely connected, and means located beyond the center sheets for supporting a running board so as not to interfere with the free floating movement of the said center sheets.

9. A flexible single layer metallic car roof including spaced floating imperforate unattached center sheets extending across the ridge or center line of the car roof and terminating at points between the ridge or center line and the eaves, side sheets secured at their side edges and constituting marginal portions of the roof, the center and side sheets having their adjacent longitudinal edges arranged in loose overlapping relation to permit free movement of the floating sheets, said center sheets having upturned flanges at their adjacent transverse edges and center sheet caps extending across the center sheets and fitting over the said flanges and terminating at the inner longitudinal edges of the side sheets.

10. A flexible single layer metallic car roof including spaced floating unattached center sheets extending across the ridge or center line of the car roof and terminating

- at points between the ridge or center line and the eaves, side sheets constituting marginal portions of the car roof and having their inner longitudinal edges arranged in loose overlapping relation with the center sheets and secured at their outer side edges at the eaves, said side sheets being provided at their adjacent transverse edges with loose joints arranged to permit relative movement of the said sheets, and center sheet caps extending across the center sheets and loosely receiving the transverse edges thereof and terminating at the inner longitudinal edges of the side sheets.
15. 11. A flexible single layer metallic car roof including spaced floating center sheets extending across the ridge or center line of the car and terminating at points between the ridge or center line and the eaves, center sheet caps spanning the space between the center sheets and loosely receiving the transverse edges thereof, side sheets having their inner longitudinal edges arranged in loose overlapping relation with the center sheets and secured at their outer side edges and provided at their adjacent transverse edges with joints composed of an upturned flange and an approximately V-shaped cap portion having substantially straight oppositely inclined sides arching the flange and loosely receiving the same and permitting independent movement of the side sheets.
12. The combination with a car body, of carlines extending across the car body, side purlins located at opposite sides of and spaced from the center line of the car body, and a flexible single layer metallic car roof including spaced floating center sheets supported at their side edges upon the side purlins, the center sheets being provided with down-turned flanges, side sheets supported upon the carlines below the plane of the center sheets and provided at their outer edges with down-turned flanges secured to the car body, the adjacent longitudinal edges of the center and side sheets being arranged in loose overlapping relation to permit easy movement of the floating center sheets, center sheet caps spanning the space between the center sheets and receiving the transverse edges of the same and terminating at the side sheets, and fastening devices located in the space between the center sheets beyond the edges thereof for connecting the said caps with the carlines.
13. The combination with a car body, of carlines extending across the car body, center and side purlins extending along the car, the center purlin constituting a ridge pole and the said side purlins being spaced from the center purlin, and a single layer metallic roof including relatively large center floating sheets extending across the space between the purlins and resting upon and supported by the same, and relatively small

side sheets arranged upon and supported by the carlines and secured at their outer edges to the car body and having their inner longitudinal edges loosely supported by the side purlins.

14. The combination with a car body, of carlines extending across the car body, center and side purlins supported by the carlines, the center purlin constituting a ridge pole, a single layer roof including relatively large center floating sheets extending across the space between and supported upon the purlins, relatively small side sheets supported upon the carlines and extending from the center sheets to the sides of the car body and secured at their outer edges to the latter, and a relatively wide running board extending substantially across the center sheets and supported beyond the edges thereof so as not to interfere with the free floating movement of the same and adapted to protect the said center sheets.

15. The combination with a car body, of carlines extending across the car body, side purlins located at opposite sides of the center of the car body and supported by the carlines, a roof including center sheets extending across the space between the purlins and spaced apart at their transverse edges above the carlines, center sheet caps spanning the spaces between the transverse edges of the center sheets, side sheets secured at their outer edges to the car body and having their inner longitudinal edges loosely supported by the purlins, the adjacent transverse edges of the side sheets being loosely supported upon the carlines and extending outwardly from the ends of the center sheet caps, side sheets caps secured to the sides of the car body and fitting over the outer ends of the transverse edges of the side sheets, running board holders provided with casings fitted over the ends of the center sheet caps and the inner ends of the transverse edges of the side sheets, and a running board supported by the said holders.

16. The combination with a car body, of carlines extending across the car body, side purlins located at opposite sides of the center of the car body and supported by the carlines, a roof including center sheets extending across the space between the purlins and spaced apart at their transverse edges above the carlines, center sheet caps spanning the spaces between the transverse edges of the center sheets, side sheets secured at their outer edges to the car body and having their inner longitudinal edges loosely supported by the purlins, the adjacent transverse edges of the side sheets being loosely supported upon the carlines and extending outwardly from the ends of the center sheet caps, running board holders having casings fitted over the ends of the center sheet caps.

and the inner ends of the transverse edges of the side sheets, fastening devices piercing the carlines and purlins and securing the running board holders to the same, and 5 a running board supported by the said holders.

17. The combination with a car body, of a carline extending across the same, center and side purlins, the center purlin constituting a ridge pole, a roof including center sheets arranged in spaced relation and supported upon the purlins, a center sheet cap spanning the space between the center sheets, a ridge pole block arranged upon the 10 center purlin and within the center sheet cap, and a fastening device piercing the ridge pole block and the center purlin and securing the same to the carline.

18. The combination with a car body, of 20 a carline extending across the same, purlins located at opposite sides of the center of the car body, a roof including center sheets spaced apart and arranged upon the purlins, a center sheet cap spanning the space between 25 the center sheets, center sheet filler blocks arranged upon the side purlins and within the ends of the center sheet cap, running board holders arranged upon the ends of the center sheet cap and supported by the said 30 blocks, and fastening devices for securing the running board holders in position.

19. The combination with a car body, of a carline extending across the same, purlins located at opposite sides of the center 35 of the car body, a roof including center sheets spaced apart and arranged upon the purlins, a center sheet cap spanning the space between the center sheets, center sheet filler blocks arranged upon the side purlins 40 and within the ends of the center sheet cap, running board holders arranged upon the ends of the center sheet cap and supported by the said blocks, and fastening devices piercing the blocks and the purlins and securing the running board holders to the 45 same and to the carlines.

20. The combination with a car body, of a carline extending across the car body, purlins located at opposite sides of the center 50 of the car body and supported upon the carline, a roof including spaced center sheets arranged upon the purlins, a center sheet cap spanning the space between the center sheets, running board holders provided with 55 upper pockets and having lower casings fitted over the ends of the center sheet cap, and a running board cross support or saddle having its ends fitted in the said pockets.

21. The combination of a car roof including spaced center sheets, a center sheet cap spanning the space between the center sheets, running board holders having lower casings fitted over the ends of the center 60 sheet cap, said running board holders being

provided at the top with pockets open at 65 the inner ends.

22. The combination of a car roof including spaced center sheets, a center sheet cap spanning the space between the center sheets, running board holders having lower 70 casings fitted over the ends of the center sheet cap, said running board holders being provided at the top with pockets each comprising a bottom, side walls and a connecting 75 outer end wall.

23. The combination of a car roof including spaced center sheets, a center sheet cap spanning the space between the center sheets, running board holders having lower 80 casings fitted over the ends of the center sheet cap, said running board holders being provided at the top with pockets each comprising a bottom, side walls and a connecting outer end wall, one of the pockets being also provided with a top wall connecting 85 the end and side walls, and fastening means carried by the other running board holder for securing a running board saddle within its pocket.

24. The combination of spaced center 90 sheets, side sheets having overlapped transverse edges arranged opposite the space between the center sheets, a center sheet cap spanning the space between the center sheets, and running board holders provided with 95 upper pockets and having lower casings fitted over the ends of the center sheet cap and provided with recesses through which the overlapped transverse edges of the side sheets extend.

25. The combination with a car, of running board holders mounted upon the car at opposite sides thereof and each composed of a lower casing, an intermediate stem extending upwardly from the casing, and an 100 upper pocket having a bottom and provided with side walls and an outer connecting end wall, and interiorly arranged fastening means for securing the running board 105 holders to the car.

26. The combination with a roof including sheets having a transverse joint or connection, of running board holders located at opposite sides of the center of the roof and each composed of a lower casing fitted over 115 the transverse joint or connection, an intermediate stem extending upwardly from the casing, and an upper pocket, and a running board provided with a cross piece fitted in the pockets of the said holders.

27. A running board holder comprising a lower casing having side walls or flanges and provided with an outer end wall or flange extending below the side walls or flanges and provided at the bottom with a 125 recess, a stem extending upwardly from the casing, and a top pocket having spaced side walls and a connecting end wall.

28. A flexible metallic car roof including relatively large unattached floating center sheets extending across the center of the car and terminating at their side edges at 5 points between the ridge or center line and the side walls and constituting the major portion of the roof, and relatively small side sheets extending from the center sheets to the eaves, the adjacent edges of the center and side sheets being loosely connected to permit free relative movement of the parts.

29. The combination of a car body, side purlins located at opposite sides of and 15 spaced from the center of the car body, carlines supporting the purlins, and a single layer flexible sheet metal roof including unattached floating center sheets extending across the space between and supported by 20 the side purlins, and side sheets supported upon the carlines in a plane below that of the center sheets and extending from the center sheets to the eaves, said side and center sheets being connected by a joint arranged longitudinally of the car and located at the said purlins.

30. The combination with a car body, carlines extending across the body, side purlins located at opposite sides of and spaced from 30 the center of the car and supported by the carlines, and a single layer flexible sheet metal car roof including unattached floating center sheets extending across the space between the side purlins and having their 35 side edges loosely supported by the same, and side sheets arranged upon the carlines in a plane below that of the center sheets and extending from the eaves to the side purlins and having their inner edges loosely 40 supported upon the said purlins.

31. The combination with a car body, of a roof including side sheets secured at their outer edges to the sides of the car body and extending inwardly from the side walls and 45 terminating short of the center line of the roof, and unattached floating sheets covering the space between the opposite side sheets.

32. The combination with a car body having a running board, of a flexible sheet metal roof including a plurality of marginal sheets extending around the sides and ends of the body and fixed at their outer edges to the same, and a plurality of unattached 50 floating sheets covering the space between the marginal sheets and loosely connected with the same and constituting the major portion of the roof, the loose connection being located nearer to the running board than to the sides of the car.

33. The combination with a car body, of a flexible sheet metal roof including a plurality of marginal sheets extending around the sides and ends of the car body and fixed

at their outer edges to the same and loosely 65 connected at their adjacent edges, and a plurality of unattached floating sheets covering the space within the said marginal sheets and loosely connected with the same and completing the roof.

34. The combination with a car body, of a flexible sheet metal roof including a plurality of marginal sheets extending around the sides and ends of the car body and fixed 70 at their outer ends to the same and loosely 75 connected at their adjacent edges, and unattached floating sheets covering the space within the marginal sheets and loosely connected at their adjacent transverse edges and also having a loose connection at the 80 inner edges of the marginal sheets, said floating sheets constituting the major portion of the car roof.

35. The combination with a car body, of a roof including side sheets secured at their 85 outer edges to the sides of the car body, and floating sheets covering the spaces between the opposite side sheets, and means for supporting a running board beyond the floating sheets, whereby a relatively wide running board is provided and free movement 90 of the floating sheets permitted.

36. A metallic car roof including floating center sheets, a running board, and means for supporting the running board beyond the center floating sheets so as not to interfere with the free movement of the same.

37. The combination with a car body, of a roof including side sheets fastened at their 100 outer edges to the car body, and center floating sheets having a loose connection with one another and with the inner edges of the side sheets, a running board, and means for supporting the running board beyond the edges of the floating sheets so as not to interfere with the free floating movement of the same.

38. The combination with a car body, of a roof including relatively narrow side 110 sheets fastened at their outer edges to the car body, and floating sheets having a loose connection with one another and with the side sheets and constituting the major portion of the car roof, running board supports 115 arranged at the side edges of the floating sheets and located beyond the same so as not to interfere with the free floating movement of the said floating sheets, and a relatively wide running board mounted on the 120 said supports and constituting a covering for the floating sheets.

39. The combination with a car body, of a metallic roof including side sheets fastened at their outer edges to the sides of the 125 car body, center floating sheets spaced apart at their transverse edges and having a loose connection with the side sheets, center sheet

caps spanning the spaces between the transverse edges of the center sheets and loosely receiving the same, a running board arranged over the center sheets, and means 5 mounted at the spaces between the center sheets for supporting the running board without interfering with the free floating movement of the said center sheets.

In testimony, that I claim the foregoing as my own, I have hereto affixed my signature in the presence of two witnesses.

WILSON E. SYMONS.
